CLAIM

The ornamental design for a curved ski, as shown and described.

DESCRIPTION

FIG. 1 is a top right perspective view of a curved ski according to a first embodiment of the present invention. FIG. 2 is a bottom right perspective view of the curved ski of FIG. 1.

FIG. 3 is a top view of the curved ski of FIG. 1.

FIG. 4 is a bottom view of the curved ski of FIG. 1.

FIG. 5 is a left side view of the curved ski of FIG. 1.

FIG. 6 is a right side view of the curved ski of FIG. 1.

FIG. 7 is a front view of the curved ski of FIG. 1.

FIG. 8 is a back view of the curved ski of FIG. 1.

FIG. 9 is a top right perspective view of a curved ski according to a second embodiment of the present invention.

FIG. 10 is a top view of a design of the curved ski of FIG. 9.

FIG. 11 is a bottom view of the curved ski of FIG. 9.

FIG. 12 is a left side view of the curved ski of FIG. 9.

FIG. 13 is a right side view of the curved ski of FIG. 9.

FIG. 14 is a front view of the curved ski of FIG. 9; and,

FIG. 15 is a back view of the curved ski of FIG. 9.

1 Claim, 13 Drawing Sheets
